UNITED STATES PATENT OFFICE.

HEZEKIAH J. BURNWORTH, OF CAMBRIDGE, OHIO.

DESIGN FOR A BOX.

SPECIFICATION forming part of Design No. 22,290, dated March 14, 1893.

Application filed February 8, 1893. Serial No. 461,624. Term of patent 7 years.

To all whom it may concern:

Be it known that I, HEZEKIAH J. BURNWORTH, a citizen of the United States, residing at Cambridge, in the county of Guernsey and State of Ohio, have invented a certain new and original Design for Boxes, of which the following is a specification, reference being had therein to the accompanying drawing, in which is represented a perspective view of the invention.

As will be seen from the drawing, the invention consists of a rectangular box or block *a* greater in length than in width, and having a rectangular pocket *b* formed in its upper surface, near one of its ends. Another pocket or recess *c* is formed in the upper surface of the box or case this pocket being shallower than pocket *b* and extending from near the

same approximately to the other end of the box, a wall *c'* being formed between the two pockets. The bottom of recess *c* is inclined gradually from the wall *c'* upwardly toward the other end of the box, terminating approximately even with its upper surface. A suitable cover *d* is hinged along one edge of the box and is provided with a suitable catch *d'*.

What I claim is—

The design for a box herein shown and described.

In testimony whereof I affix my signature in presence of two witnesses.

HEZEKIAH J. BURNWORTH.
